UNITED STATES PATENT OFFICE.

WILLIAM TAYLOR, OF KEUKA COLLEGE, NEW YORK.

HARNESS-SADDLE.

SPECIFICATION forming part of Letters Patent No. 511,474, dated December 26, 1893.

Application filed May 24, 1893. Serial No. 475,331. (No model.)

To all whom it may concern:

Be it known that I, WILLIAM TAYLOR, a citizen of the United States, residing at Keuka College, in the county of Yates and State of New York, have invented a new and useful Improvement in Harness, of which the following is a specification.

This invention relates to an improved harness.

10 One of the objects of my invention is the production of a saddle which permits a free circulation of air around the saddle, so as to prevent soreness resulting from undue perspiration under the saddle, and which is not liable to tilt or rock and thus gall or cut the horse's back.

15 My invention has the further objects to so construct the harness that, if desired, the breeching may be dispensed with, and to support the thill loops in such a manner that they may be shifted backward or forward to bring the weight of the thills on any desired portion of the saddle.

20 In the accompanying drawings:—Figure 1 is a side elevation of my improved harness. Fig. 2 is a front view thereof. Fig. 3 is a detached perspective view of the rigid frame which connects the two saddle pads. Fig. 4 is a side elevation of a modified construction 25 of the harness.

Like letters of reference refer to like parts in the several figures.

25 My improved saddle consists essentially of two transverse pads A A', arranged one in front of the other and connected by a rigid metallic frame B. These pads are comparatively narrow, so as to present a small bearing surface, and they are arranged a short distance apart, say from five to seven inches, 30 so as to leave an intervening space between them. By constructing the saddle in this manner the same has two bearing surfaces located on opposite sides of its transverse center, whereby rocking or tilting of the saddle is prevented and galling or chafing of the horse's back is avoided. The connecting frame B consists of transverse bars $b b'$ secured to the upper sides of the pads, respectively, and shaped to conform to the pads, longitudinal bars $b' b'$, connecting the ends of the transverse bars and a longitudinal central bar b^2 , connecting the raised middle portions of the

transverse bars. The rectangular spaces c between the bars of this connecting frame coincide with the spaces which separate the pads 55 and permit the air to circulate freely between the pads, thus obviating heating of the horse's back and preventing soreness.

The connecting frame B is preferably cast in a single piece, but, if desired, it may be 60 constructed of separate bars.

d is the usual back strap attached at its front end to the saddle and carrying at its rear end the crupper, which is not shown in the drawings.

65 E E' represent a pair of belly bands attached respectively to the back straps F F', extending downward from the saddle pads.

g represents thill straps attached to the under side of the belly bands on opposite sides 70 of the harness, and adapted to be tightly secured with their free outer portions to the adjacent portions of the thills H, preferably by winding the straps around the thills a number of times, and engaging their ends with 75 buckles g' arranged on the strap, so as to prevent slipping on the thills. Four of such straps are employed, two being arranged on each belly band, so that each thill is embraced by two straps. This positive and direct communication of the thills with the saddle, enables the vehicle to be backed without the use of the usual breeching, thus materially simplifying and cheapening the harness.

80 If desired, a single belly band may be employed, in which case the band is attached centrally to the saddle, as shown at E² in Fig. 4.

I I represent the thill loops through which the thills are loosely passed in the usual manner, and which are suspended from the saddle by supporting straps j arranged on opposite sides of the harness, between the back-straps F. The upper ends of the supporting straps are removably attached to the longitudinal side bars b' of the saddle by screws, 95 so that the straps may be shifted backward or forward on the saddle, if desired, for bringing the weight of the thills at the front or back of the saddle, or in the middle thereof. For this purpose the saddle is provided on 100 each side with three attaching screws k k' k² arranged one in front of the other, the terrets constituting, preferably, the rear screws or attachments of said straps.

I claim as my invention—

1. A harness saddle comprising the two narrow transverse pads arranged with a space between them, and the means for connecting and holding said pads together consisting of a rigid frame extending over them and made up of angular transverse portions conforming substantially to the pads and connected by rigid longitudinal side bars, the back bands extending down from the pads in front and rear of the saddle, 5 the belly bands connected to the back bands, the thill loops and the straps carrying the same and adjustably connected at their upper ends with the longitudinal bars extending between the pads whereby said straps may be 10 fixed at different points on the side bars to shift the weight of the thills, substantially as described.

15 2. A harness saddle comprising the two narrow pads arranged with a space between them, the means for connecting and holding said pads together consisting of a rigid frame

extending over them and made up of angular transverse portions conforming substantially to the pads and connected by rigid longitudinal side bars, the back bands extending down from the pads in front and rear of the saddle, 25 the belly bands connected to the back bands, the thill loops and the straps carrying the same and adjustably connected at their upper ends with the longitudinal bars extending between the pads whereby said straps may be 30 fixed at different points on the side bars to shift the weight of the thills, substantially as described.

Witness my hand this 18th day of May, 1893.

WILLIAM TAYLOR.
